Primary Examiner — Jae Liang

Assistant Examiner — Bryan Coauhemic Gusman

(74) Attorney, Agent, or Firm: — Workman Nydegger

(57) CLAIM

The ornamental design for a desk, as shown and described.

DESCRIPTION

FIG. 1 is a front perspective view of a desk showing the new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof;

FIG. 7 is a bottom plan view thereof; and,

FIG. 8 is another front perspective view thereof with drawer in an open configuration.

The broken lines shown in the figures illustrate portions of the desk that form no part of the claimed design.

1 Claim, 6 Drawing Sheets

US D995,162 S
